UNITED STATES PATENT OFFICE.

GEORGE A. TAYLOR, OF WEEHAWKEN, NEW JERSEY, ASSIGNOR TO NATIONAL BISCUIT COMPANY, OF NEW YORK, N. Y., A CORPORATION OF NEW JERSEY.

DISPLAY COVER.

Application filed September 8, 1921. Serial No. 499,232.

This invention has reference to a cover and particularly aims to provide a device of this character primarily adapted for association with a receptacle for the purpose of 5 attractively displaying the contents thereof.

It is an object of the present invention to provide a cover which will efficiently perform the functions for which it is intended and which will also be economically and 10 readily manufactured and assembled.

It is a further object to provide a cover of improved construction which may be applied to a receptacle in which merchandise is shipped and stored and after such merchandise 15 is to be placed on display.

A still further object resides in the provisions of a device of the character stated which when used for the purpose of displaying articles within a container will enhance 20 the appearance of the receptacle and serve to provide an attractive display for the merchandise aside from the fact that when the cover is in use the contents of the receptacle are readily accessible.

Another object of this invention is that which permits the shipment of merchandise in receptacles of any desired construction and material, which receptacles may be closed by a cover associated with the same 25 and in which, when the merchandise is to be placed on display, this cover may be moved to a position at which it will not be noticeable to the observer, or in fact may be entirely removed from the receptacle and the improved cover of the present invention may 30 be substituted therefor so that the goods while on display present an extremely attractive appearance, aside from the fact that when the receptacle has been emptied, the body of the same may be discarded and the 35 last named cover may be removed therefrom and subsequently utilized on another receptacle.

Thus, it is obvious for example, that the 40 retailer may have in his possession a number of these display covers and the filled receptacles are shipped to him and after being opened, the improved display covers may be applied thereto and retained in association 45 therewith while the receptacles are in active use and after the contents of the receptacles become exhausted, the latter may be discarded or returned to the manufac-

turer so that the relatively expensive covers utilized are not wasted or liable to become 55 broken in shipment.

Other objects of the invention will in part be obvious and will in part appear herein-after.

The invention accordingly comprises an 60 article of manufacture possessing the features, properties, and the relation of elements which will be exemplified in the article hereinafter described and the scope of the application of which will be indicated in 65 the claims.

For a fuller understanding of the nature and objects of the invention reference should be had to the following detailed description taken in connection with the accompanying 70 drawing, in which:

Fig. 1 is a perspective view of a cover embodying the improved construction of the present invention and showing the same applied to a receptacle of the type specified, 75

Fig. 2 is a top plan view of the cover,

Fig. 3 is a sectional plan view taken along the lines 3-3 and in the direction of the arrows indicated in Fig. 1,

Fig. 4 is a fragmentary sectional side view 80 of the lower portion of the cover construction, and taken along the lines 4-4 and in the direction of the arrows indicated in Fig. 6,

Fig. 5 is a sectional side view taken along 85 the lines 5-5 and in the direction of the arrows indicated in Fig. 1,

Fig. 6 is a rear view of the cover, and

Fig. 7 is a fragmentary sectional side view 90 of the upper portion of the cover and taken along the lines 7-7 and in the direction of the arrows indicated in Fig. 6.

The cover herewith shown has been illustrated in association with a receptacle of the type commonly used for the shipment and storage of bakers' products such as biscuits, crackers, etc., and to which use, the cover is particularly applicable, it being understood however that the same may be employed to advantage for the display of numerous other classes of merchandise. 95

Thus, the receptacle includes a body 1, to which for the purpose of shipment and storage, a cover 2 may be secured in any desirable manner such as, for example, by hing- 100 edly attaching these elements one to the

other as has been indicated at 3, it being, perceived in the present instance that the cover 2 is formed with depending flanges 4 so that the goods contained within the receptacle will be protected against damage.

Now, referring to the construction of the display cover which is to be applied to the receptacle after the initial cover of the latter is moved to the position shown in Figs. 1 and 5, it will be seen that a main frame is utilized. This frame includes a body having rearwardly extending flanges 5, 6 and 7, having their rear or outer edge-portions bent upon their bodies in order to strengthen the structure. The flange 7 may be interrupted throughout a portion of its length, so that it is divided into two sections, one disposed adjacent each of the upper and side edges of the main frame, the purpose 20 of this construction becoming hereinafter apparent.

For the sake of economy in manufacture as well as providing an article which will withstand a reasonable amount of rough usage in addition to presenting a neat and attractive appearance, the frame may be formed of sheet metal and what has been termed the body of this frame may include portions 8, 9 and 10 which are bent to 30 extend substantially at right angles to the flange portions afore-mentioned. It will furthermore be noted that strips 11 are preferably attached to the rear face of the frame body and these strips have their front faces 35 lying in contact with the rear faces of the portions 8, 9 and 10, the width of the strips 11 being such that they extend beyond the inner edges of the portions afore-referred to and are bent outwardly and preferably 40 upon themselves to form rigid forwardly extending flanges 12, 13 and 14.

Hingedly attached to the frame thus provided, and preferably adjacent one of the inner edges of the body thereof, as at 15, is a closure in the nature of a door which in one dimension at least, (in the present instance, its width) is less than the corresponding portion of the frame. This door includes an auxiliary frame 18, the body of 50 which is preferably formed with an upper opening and a lower opening, the latter being conveniently of a size materially greater than the upper opening. These openings are adapted to accommodate panels 16 and 55 17, the former preferably being a sheet of transparent glass while the latter may be in the nature of a name plate, by means of which the name of the manufacturer of the goods displayed in the container is brought 60 before the public, and in order to enhance the attractiveness of the display, the body 18 adjacent each of these openings, may be formed with beads 19 and 20, if it is so desired.

65 The purpose of the forwardly extending

flanges 12, 13 and 14 will now become apparent in that these flanges are preferably of a length sufficient to have their forward edges lie adjacent to the rear face of the auxiliary frame 18 while the rearwardly extending flanges 21, forming a part of the latter, overlie the first named flanges and have their rear edges extending to points adjacent to the main frame body. Thus, a jamb is furnished for the door and a seal 75 is provided which is adequate to prevent the entrance of foreign matter into the receptacle body so that the merchandise within in the same is maintained in a desirable condition.

In order to retain the panel 16 in applied position upon the frame 18, a strip 22 may be utilized, which extends adjacent both the lower edge of this panel and that of the frame, and this strip may be suitably associated with the frame in any desirable manner and bears against the inner face of the panel 16 to thus effectually prevent movement of the latter relative to the auxiliary frame at this point. At this point the door 90 may carry a card holder 22' so that a card retained thereby will be held in such a manner that it will be displayed behind the panel 16. The panel providing the name plate 17 may also be attached to the frame 95 in any desirable manner such as, for example, by utilizing lugs 23 which extend from the rear face of the frame and overlie the rear face of this panel adjacent the upper edges of the latter. The adjacent edges of the 100 panels, i. e., the lower edge of the panel 17 and the upper edge of the panel 16, in the present embodiment, are anchored against movement by utilizing strips 24 and 25 respectively which are L-shaped in cross-section and which may be secured to the frame 18 in any suitable manner, as by soldering. As is clearly brought out in Figure 5, these strips extend outwardly from the frame 18 between the panels 17 and 16 110 and extend upwardly and downwardly respectively along the inner surfaces of these panels so as to hold them in place. These strips are reinforced by a further strip 27 which may be soldered to either or both of these strips—for example to the strip 23. As will be seen upon examination of Fig. 5 the strip 27 bears closely against both of the strips 24 and 25 so as to reinforce each 120 of these strips regardless of whether it is soldered to both of the strips or only as to one of them, as strip 25.

With a view to the provision of facilities for the accommodation of a card or tag such as identifies the particular class of goods 125 displayed, a member 28 having an upturned lower edge 29 may be affixed to one of the aforementioned strips by being soldered thereto at its ends as at 28'. The member 28 is in the present instance spaced from 130

the strip 27 throughout the greater portion of its length so that a card 30 may be inserted in the pocket 26 thus provided and may be visible through the pane of glass 16, it being noted that the strip 27 extends downwardly only a short distance beyond the top of member 28. An inspection of Fig. 1 will reveal that this pocket 26 extends across only a comparatively small portion 10 of the opening covered by the panel 17, so as to cut off as little as possible the view of the contents of receptacle. A notch 31 is provided in the upper edge of the member 38 to permit the ready removal of the card 30 when desired. It will be seen that in the particular construction illustrated, the members 27 and 28, being soldered as at 28' to each other and to the strip 25, form a unitary means for holding a card and for 20 re-enforcing the holding strip 24 against which the strip 27 bears closely as pointed out above.

In use it will be understood, assuming that a retailer be opening a filled receptacle, 25 he simply swings the cover to the position shown or else entirely discards this cover according to the type and material of the receptacle. In either event, the frame is now ready for application to the receptacle 30 to provide a cover for the opening thus established and this application is obviously accomplished by telescoping the frame upon the receptacle so that the flanges 5, 6, and 7 occupy a position flush against certain of 35 the faces (in the present instance the outer) of the receptacle walls. The purpose of the construction of the flange 7 will now become apparent in that the interrupted portion of this flange is sufficient to accommodate 40 the hinges 3 which may connect the cover with the body of the receptacle so that in other words, the parts of this flange may slide to occupy positions to one side of the points of hinged connection and between 45 the cover and receptacle bodies, it being of course, understood that if the cover is entirely discarded, and if this construction is employed this flange together with the other flanges, will be adequate despite the 50 interrupted portion thereof, to effectually anchor the frame to the receptacle body. This anchoring in any instance, is to be predicated to the intimate and frictional contact established between certain portions 55 of the inner faces of the flanges and the faces of the receptacle walls and it is obvious that when the frame is properly applied, the outer edge portions of the receptacle walls will lie adjacent the inner faces 60 of the main frame.

The receptacle is now preferably swung so that the display cover applied thereto becomes one of the side walls of the container and as a consequence, the merchandise within 65 the receptacle body is effectually displayed

together with the name of the manufacturer, if the panel 17 is utilized, and it is obvious that the door when in closed position will provide a closure adequate to protect the articles within the receptacle although this 70 door may readily be swung through a single plane on a substantially vertical axis to a position at right angles to the main frame so that the dealer may have access to the merchandise for the purpose of dispensing 75 the same.

Cards or tags may now be associated with either or both of the elements 22' or 28. It will be apparent in either instance that these cards will be visible through the panel 16 80 so that, for example, the class of goods and the price of the same may be shown. However, these cards will not interfere with the display of the articles within the receptacle 85 due to the fact that the cards are materially smaller than the transparent panel through which they are visible.

It will be understood, in use, that the receptacles with the covers applied are preferably arranged upon a rack or shelf, one 90 beside the other, and usually in more or less intimate contact with each other due to the limitation of space usually existing, and also to improve the attractiveness of the display. When the receptacles are so arranged, the 95 auxiliary frames or doors of the display covers may be freely swung relative to the main frames thereof. This is due to the fact that in the present instance the width of these auxiliary frames is less than the width 100 of the receptacles and main frames, and thus the side edges of one door will not bear against or come into contact with similar edges forming a part of the doors of adjacent receptacles. 105

Since certain changes may be made in the above article and different embodiments of the invention could be made without departing from the scope thereof, it is intended that all matter contained in the above description or shown in the accompanying drawings shall be interpreted as illustrative and not in a limiting sense. 110

It is also to be understood that the following claims are intended to cover all of the generic and specific features of the invention herein described, and all statements of the scope of the invention which, as a matter of language, might be said to fall therebetween. 115

Having described my invention, what I claim as new and desire to secure by Letters Patent, is:

1. A display cover for association with the open side of a receptacle, said cover being 125 formed of sheet metal and including a main frame, continuous flanges extending rearwardly from three edge portions thereof, a pair of spaced flanges extending rearwardly from the fourth edge of said frame and 130

disposed adjacent the ends of said fourth edge, all of said flanges being adapted for engagement solely with similar faces of said receptacle to maintain the body of said frame applied to said receptacle, and an auxiliary frame hingedly secured to one of the sides of said main frame.

2. A display device, including a rigid sheet metal frame formed with a pair of 10 openings, panels to the rear of said openings, a metal strip fixed to the inner face of the frame and at points beyond the panels, said strip bearing directly and frictionally against the inner faces of said panels to 15 retain the same in position against the inner face of the frame, and a main frame to which said first named frame is swingingly secured.

3. A cover for receptacles, including a 20 main frame, rearwardly-extending flanges forming a part of said frame, an auxiliary frame hingedly secured to said main frame, said main frame being adapted for application to a receptacle having an initial cover 25 movably attached to its body, said first-named frame being adapted to be applied to said receptacle after the cover of the latter has been moved to open the receptacle and to have its flange portions telescopically 30 disposed relatively to and in intimate contact with certain of the wall faces of the receptacle whereby to retain said main frame in fixed position thereon, said last-named frame having portions disposed between the adjacent 35 faces of the receptacle cover and body to accommodate the initial receptacle cover in such position.

4. A display cover for receptacles including a frame having a plurality of openings 40 therein, a panel positioned across one of said openings, means to hold said panel in position, a transparent panel across another of said openings and means adapted at once to reinforce said holding means and to receive 45 a card in a position in which it is visible through said transparent panel.

5. A display cover for receptacles including a frame having a plurality of openings 50 therein, a panel positioned across one of said openings, means to hold said panel in position, a transparent panel across another of said openings and means permanently affixed to said frame and adapted at once to reinforce said holding means and to receive a 55 card in a position in which it is visible through said transparent panel.

6. A display cover for receptacles comprising a main frame provided with rearwardly extending flanges adapted to be telescopically disposed relative to, and to frictionally bear against, certain of the faces of the receptacle walls, an auxiliary frame movably attached to said main frame, upper and lower openings in said auxiliary frame, a 65 panel positioned across said upper opening,

means to hold said panel in position, a transparent panel positioned across the lower opening and unitary means adapted at once to reinforce said holding means and to receive a card in a position in which it is visible through said transparent panel. 70

7. A cover for receptacles comprising a main frame formed of sheet material, rearwardly extending flanges adapted to telescope over and frictionally bear against the outer faces of the receptacle walls, an auxiliary frame movably attached to said main frame, said auxiliary frame being formed with a pair of openings, panels for covering such openings, a pair of strips, one of said strips contacting with the rear face of one of said panels, the other strip contacting with the rear face of the other of said panels, said strips being in contact with each other around adjacent edges of the two panels, 80 and means for securing said strips in position whereby to retain said panels applied to said auxiliary frame. 85

8. In containers, the combination of a container having a cover hinged thereto and adapted to be swung back against the top of the container, a separable display cover having a top flange to be inserted between the top of the container and the hinged cover when the latter is swung back, and other 90 flanges adapted to engage against other outer surfaces of the container, adjacent to the front thereof. 95

9. In containers, the combination of a container having a cover hinged thereto and 100 adapted to be swung back against the top of the container, and a separable display cover member comprising a frame having a top flange to be inserted between the top of the container and the hinged cover thereof when 105 the latter is swung back, and other flanges adapted to engage against other outer surfaces of the container, adjacent to the front edges thereof, and a closure member hinged to said frame and adapted to seat in closed 110 position against said frame. 110

10. In containers, a cover member having upper and lower adjacent openings, a strip secured to the rear surface of said member above the lower opening and extending 115 downwardly to retain the upper edge of a pane covering said opening, an upwardly extending strip above said first strip for retaining the lower edge of a plate covering said upper opening, and a pocket for a removable label strip comprising a front strip secured to said first strip and extending up over said second strip and a rear strip secured at its ends to said first strip and extending downwardly a short distance rearwardly from said front strip, in alignment therewith, said rear strip having a forwardly extending bottom flange to form a label strip support. 120

11. In containers, a cover member having 130

an opening therethrough, a strip secured to the rear surface of said member above said opening and extending downwardly to retain the upper edge of a pane covering said opening, and a pocket for a removable label strip comprising a front strip secured to said first strip and extending upwardly a short distance and a rear strip secured at its ends to said first strip and extending downwardly a short distance rearwardly from said front strip, in alignment therewith, said rear strip having a forwardly extending bottom flange to form a label strip support.

12. In containers, a cover member having an opening therein, a pane positioned behind and covering said opening, an angular strip bearing against the upper edge of said pane and the rear surface thereof adjacent to its upper edge, to retain the upper edge of said pane in place, and a pocket for a removable label strip extending below said angular strip, into position to be visible through the upper portion of said pane.

13. In containers, a cover member having upper and lower adjacent openings, a name plate positioned behind the upper and a pane behind the lower opening, and an angular member bearing against the upper edge of said pane and the rear surface thereof adjacent to its upper edge to retain said upper edge in place, a further angular member having an upwardly extending portion behind said name plate exerting pressure thereon, and a member extending below said angular members and constituting a pocket for a removable label strip, so positioned as to be visible through the upper portion of said pane.

14. A cover for receptacles including a main frame, rearwardly-extending flanges on four sides of said frame and forming a part of said frame, an auxiliary frame hingedly secured to said main frame, said main frame being adapted for application to a receptacle having hingedly attached thereto an initial cover flanged on two sides adjoining the hinge, said first-named frame being adapted to be applied to said receptacle after the initial hinged cover of the latter has been moved to open the receptacle, so that three of its flange portions will be telescopically disposed relative to, and in intimate contact with, three of the wall faces of the receptacle, the flange on the fourth side of the frame being located closely adjacent the receptacle wall, there being a cut-out portion in a flange of the main frame to permit application of the cover to the receptacle, without interference of the initial hinged cover.

15. In containers, the combination of a container having a cover hinged thereto and adapted to be swung back against an outer surface of the container, a separable display cover having a flange to be inserted

between the said outer surface of the container and the hinged cover when the latter is swung back, and other flanges adapted to engage against other outer surfaces of the container adjacent the open side thereof.

16. In containers, the combination of a container having a cover hinged thereto and adapted to be swung back against an outer surface of the container, a separable display cover having a flange to be inserted between the said outer surface of the container and the hinged cover when the latter is swung back, and other flanges adapted to engage against other outer surfaces of the container adjacent the open side thereof, and a closure member hinged to said display cover and adapted to seat in closed position against said display cover.

17. An auxiliary cover for containers having each a hinged lid, comprising a portion adapted to frictionally grip the faces of the container and having a sight opening through which the contents of the container may be seen, said auxiliary cover being entirely outside of said container and the portion thereof adapted to frictionally grip the upper portion of the container having a cut-out portion within which the lid hinges of the container are located.

18. An auxiliary cover for containers having each a hinged lid, comprising a body including a portion adapted to frictionally grip the faces of the container, said portion of said auxiliary cover being provided with a cut-out portion within which the lid hinges of the container are located, a lid hinged to said body, said lid being provided with a sight opening, and a sheet of glass covering said sight opening through which the contents of said container may be seen, said gripping portion of said auxiliary cover and the hinged lid associated therewith being entirely outside of said container.

19. An auxiliary cover for containers having each a hinged lid, comprising a portion adapted to be pressed over the upper portion of a container, said portion of said auxiliary cover being provided with a cut-out portion within which the hinges of the container are located, and said cover having a sight opening through which the contents of the container may be seen.

20. A display device formed of metal and including parts bent to provide a frame body, the latter comprising rearwardly-extending flanges, portions extending at substantial right angles to and from the forward edges of the flanges, further flange portions extending forwardly at the inner edges of said latter portions, and a cover including a body and flanges extending rearwardly therefrom, and means providing a hinge coupling one of the latter flanges to one of the angular frame portions; the flanges of said cover, when the latter is seat-

ed upon the frame, lying immediately adjacent the forwardly-extending flanges of said frame.

21. A display device formed of metal and including parts bent to provide a frame body, the latter comprising rearwardly-extending flanges having inturned portions at the rear edges thereof, portions extending at substantial right angles to and from the forward edges of the flanges, further flange portions extending forwardly at the inner edges of said latter portions, said latter flange portions having their edges bent inwardly upon their bodies, and a cover including a body and flanges extending rearwardly therefrom, certain of said latter flanges having their edges turned upon their bodies to extend forwardly, and means providing a hinge coupling one of the latter flanges to one of the angular frame portions; the flanges of said cover, when the latter is seated upon the frame, lying immediately adjacent the forwardly-extending flanges of said frame.
22. A display device formed of metal and including parts bent to provide a frame body, the latter comprising rearwardly-extending flanges, portions extending at substantial right angles to and from the forward edges of the flanges, further flange portions extending forwardly at the inner edges of said latter portions, a cover including a body and flanges extending rearwardly therefrom, and means providing a hinge coupling one of the latter flanges to one of the angular frame portions; the flanges of said cover, when the latter is seated upon the frame, lying immediately adjacent the forwardly-extending flanges of said frame, the cover presenting four side edges, and the frame having a shape corresponding to that of the cover, the upper and lower cover flanges being spaced a distance substantially equal to the distance between the corresponding rearwardly-extending frame flanges, the distance between the side cover flanges being appreciably less than the distance between the rearwardly-extending frame flanges which are adjacent thereto so that when the cover is in seated position upon the frame parts of the right angle frame portions will be exposed beyond the side edges of the cover.

tially equal to the spacing between the rearwardly-extending flange portions of the frame which are adjacent thereto, the two other cover flanges being spaced from each other a distance less than the distance between the corresponding rearwardly-extending frame flange portions to expose parts of the surfaces of the right angle portions of the frame when the cover is in seated position thereon.

23. A display device formed of metal and including parts bent to provide a frame body, the latter comprising rearwardly-extending flanges, portions extending at substantial right angles to and from the forward edges of the flanges, further flange portions extending forwardly at the inner edges of said latter portions, and a cover including a body and flanges extending rearwardly therefrom, and means providing a hinge coupling one of the latter flanges to one of the angular frame portions; the flanges of said cover, when the latter is seated upon the frame, lying immediately adjacent the forwardly-extending flanges of said frame, the cover presenting four side edges, and the frame having a shape corresponding to that of the cover, the upper and lower cover flanges being spaced a distance substantially equal to the distance between the corresponding rearwardly-extending frame flanges, the distance between the side cover flanges being appreciably less than the distance between the rearwardly-extending frame flanges which are adjacent thereto so that when the cover is in seated position upon the frame parts of the right angle frame portions will be exposed beyond the side edges of the cover.

Signed at New York, in the county of New York and State of New York, this first day of September A. D. 1921.

GEORGE A. TAYLOR.
